US0D1018521S

(12) **United States Design Patent** (10) **Patent No.:** **US D1,018,521 S**
(45) **Date of Patent:** **** Mar. 19, 2024**

(54) **CABINET FOR COMPUTER EQUIPMENT**

(71) Applicant: **Rubber Road Ltd.**, Hertfordshire (GB)

(72) Inventor: **Karl Mizen**, Jarrow (GB)

(73) Assignee: **Rubber Road Ltd** (GB)

(**) Term: **15 Years**

(21) Appl. No.: **29/885,438**

(22) Filed: **Feb. 24, 2023**

Related U.S. Application Data

(62) Division of application No. 29/754,038, filed on Oct. 6, 2020, now Pat. No. Des. 983,192.
